UNITED STATES PATENT OFFICE.

EMERICH THERN, OF BOSTON, MASSACHUSETTS.

DESIGN FOR A BOWL FOR TOBACCO-PIPES.

47,476.

Specification for Design.

Patented June 15, 1915.

Application filed January 18, 1915. Serial No. 2,990. Term of patent 3½ years.

To all whom it may concern:

Be it known that I, EMERICH THERN, a citizen of the United States, residing at Boston, in the county of Suffolk and State of Massachusetts, have invented a certain new, original, and ornamental Design for the Bowl of a Tobacco-Pipe, of which the following is a specification, reference being had to the accompanying drawings, forming part thereof, in which—

Figure 1 is a plan view of the bottom of

the design; Fig. 2 is a plan view of the top of the design; Fig. 3 is a side elevation of the design; Fig. 4 is a perspective view of the design.

I claim:

The ornamental design for the bowl of a tobacco pipe as shown.

EMERICH THERN.

Witnesses:

JOSEPH T. BERMAN,
MARY A. NYHAN.
